(57) CLAIM

The ornamental design for a rotational frame of spinning reel, as shown and described.

DESCRIPTION

FIG. 1 is a front elevational view of a rotational frame of spinning reel in accordance with my new design;

FIG. 2 is a rear elevational view of the rotational frame of spinning reel in accordance with my new design;

FIG. 3 is a top plan view of the rotational frame of spinning reel;

FIG. 4 is a bottom plan view of the rotational frame of spinning reel;

FIG. 5 is a right side elevational view of the rotational frame of spinning reel;

FIG. 6 is a left side elevational view of the rotational frame of spinning reel;

FIG. 7 is a cross-sectional view of the rotational frame of spinning reel in accordance with my new design viewed in the direction of arrow 7—7 in FIG. 1; and

FIG. 8 is a cross-sectional view of the rotational frame of spinning reel in accordance with my new design viewed in the direction of arrow 8—8 in FIG. 2; and

FIG. 9 is a cross-sectional view of the rotational frame of spinning reel in accordance with my new design viewed in the direction of arrow 9—9 in FIG. 3; and,

FIG. 10 is a perspective view of the rotational frame of spinning reel.

The broken line showing of environment (the remaining structure of the rotational frame of spinning reel) in the Figures is for illustrative purposes only and forms no part of the claimed design. Moreover, is hereby disclaimed. The rear side of the rotational frame of spinning reel does not form part of the claimed design.
